UNITED STATES PATENT OFFICE.

ARTHUR McDougall DUCKHAM, OF LONDON, ENGLAND.

GASIFICATION OF COAL OR OTHER CARBONACEOUS MATERIAL.

Application filed May 2, 1921. Serial No. 466,223.

To all whom it may concern:

Be it known that I, SIR ARTHUR McDougall DUCKHAM, a subject of the King of Great Britain, residing in London, England, have invented certain new and useful Improvements in Gasification of Coal or Other Carbonaceous Material, of which the following is a specification.

This invention relates to plants and processes for the gasification of coal and of other carbonaceous materials in which, in addition to the destructive distillation of the hydrocarbons contained in the material, the residue is utilized for the manufacture of water gas. The destructive distillation is accomplished both by the external heating of the retort or chamber containing the material, and by the passage of the hot water gas through the material.

The usual type of apparatus utilized for this purpose is a vertical retort or chamber constructed with external heating flues, superimposed on a generator so constructed that the material is discharged or automatically discharges itself, while still hot, from the retort or chamber into the generator. The water gas is made by heating the material in the generator by first blowing air through the fuel bed; the products of combustion pass into the external heating flues of the retort or oven at the bottom and travel upwards, so providing heat for the carbonization of the material; when the fuel bed has attained a sufficient temperature the air supply is shut off and steam introduced into the generator and to make water gas which is caused to pass from the generator portion of the plant through the retort or chamber, assisting carbonization by its sensible heat and carrying forward from the retort a proportion of the lighter hydrocarbons which would otherwise be deposited with the tar in the condenser.

The purpose of the present invention is to improve this general method of working. In the first place, to obtain the best results of carbonization it is desirable that the greatest external heat should be applied to the upper portions of the retort or chamber; products of combustion from the blow, that is the heating up of the fuel bed in the generator portion of the plant, are taken by means of a suitable flue or flues to the upper

portion of the retort or chamber and distributed to the external heating flues so as to obtain the desired effect. In the second place, the amount of heat available from the products of combustion made during the blow and the sensible heat of the water gas which passes through the material in the retort or chamber do not give a sufficient temperature to complete the proper carbonization of the material before it enters the generator, and consequently a certain amount of hydrocarbons pass away with the blow gases. In order to obtain the increased external heat required for carbonization, arrangements are made to utilize for the purpose a portion of the water gas made in the generator part of the plant, taking the water gas by means of suitable flues and consuming it in the same external flues as are heated by the products of combustion from the generator during the blow period of working.

In a series of such plants it may be advisable for convenient working to utilize the gases formed during the blow period for heating the boiler, or boilers, which will supply steam for the purpose of making water gas rather than for the heating of the carbonizing vessel. Under these conditions the whole of the external heating of the retort may be carried out either by means of water gas from the generator direct or by means of the mixed gases from the retort.

Inasmuch as the products of combustion formed during the blow period will contain a certain proportion of combustible gases, arrangements are made for the admission of a secondary air supply to the parts at which the products of combustion enter the external heating flues of the retorts or chambers, this secondary air preferably being heated by the waste gases leaving the external heating flues. The secondary air supply will also be utilized for the combustion of the water gas taken from the generator for the purpose of heating the retorts or chambers during that period of the operation where water gas is being manufactured in the generator portion of the plant.

In the accompanying drawings:—
Figs. 1 and 2 are vertical sections, in planes at right angles to each other, through

a combined generator and retort constructed in accordance with the invention.

Figs. 3 and 4 show a vertical section and a horizontal section respectively through 5 a series of such retorts slightly modified.

In the setting *a* the retort or carbonizing chamber, which is of rectangular horizontal section, and tapers upwards, is supported on an arch *b*. The spaces between the walls *c* 10 and the setting are subdivided into flues *d*, communicating at the top with pipe *e* destined to convey to these flues the gases for externally heating the retort. The lower ends of the flues *d* communicate with 15 the waste gas flue *g*.

The lower portion of the setting *a* consists of a generator, of suitable dimensions for producing the water gas from the residual carbonizing material, preferably of a type 20 that permits of continuous removal of the ashes.

In this instance, the products of combustion from the air blast *h* are led to the top of the installation by the pipe *e* where they 25 are distributed to the heating flue *d* by means of the flue *r*, secondary air for their proper combustion being admitted by the flue *p*. Steam is admitted at *l*, and the water gas passes up through the carbonizing vessel, a portion being taken by means 30 of the pipe *n* through valve *o* to the flue *e* where it is distributed in a similar manner as the blow gases to the heating flues.

For the purpose of the invention there is 35 a communication *n* between the annular flue *i* and the pipe *e*, controlled by a valve *o*, and the operation is as follows:—

The coal or the like, fed continuously or 40 intermittently in known manner into the top of the retort at such a rate that the latter and the generator are always full, enters in more or less completely carbonized condition into the generator. Here it is blown to the necessary degree of incandescence by 45 the air blast introduced at *h* and the products of combustion pass from the heating flues as described above. During this blow period the valve *o* remains open, and the steam supply at *l* is cut off. When the fuel 50 in the generator has been sufficiently heated, the air valve *s* is closed and the steam valve *u* is opened. Steam now ascends the generator and the water gas formed passes mainly up the retort.

55 A certain proportion of the water gas passing through the annular flue *i* is conveyed through the pipe *e* to the heating flues at the top of the retort. The proportion of the water gas utilized for this purpose is controlled by regulating the valve *o*.

The setting is shown in the drawing as comprising only one retort, but by suitable modification a single generator may serve a setting including a number of retorts.

60 In Figs. 3 and 4, in the setting *a* retorts

or carbonizing chambers *a*¹, *a*², *a*³, *a*⁴ of rectangular horizontal section and tapering upwards are supported on arches *b*. Heating flues are formed about these retorts or carbonizing chambers in a similar manner 70 to that shown in Figs. 1 and 2, and there is a generator beneath each retort or carbonizing chamber. In this instance, the products of combustion from the air blast *h* are led from the top of the generator through 75 the annular flue *i* by means of ports *k* to collecting flue *t* which carries these gases to the boilers for the purpose of raising steam for the generation of water gas.

During the run period steam is admitted 80 through the pipe *l* and steam valve *u* to the generator. The water gas formed either passes up through the retort or carbonizing vessel where it mixes with the gases evolved from the coal, or should it be desired to 85 heat the retort with water gas alone the water gas is taken through the valve *o* to the flue *e* and by means of the valve *o*¹ admitted to the distributing flues *r* at the top of the setting. Should it be desired to heat 90 the retorts or carbonizing chambers with the water gas after it has been mixed with the gases evolved in the retort, these gases are returned from the pipe *x* through the valves *o*² and *o*¹ to the heating flues *r*, the valve *o* 95 remaining closed during the whole of such operation. It will be seen that with a battery of four of such units there will be a continuous supply of steam available from the blow gases to the boiler and at the same 100 time a continuous supply of water gas from the generators for heating the retorts or carbonizing vessels.

Having thus described the nature of the said invention and the best means I know 105 of carrying the same into practical effect, I claim:—

1. A process of gasifying coal and the like, which consists in carbonizing as completely as practicable the material in an 110 externally heated vessel, receiving the residue from said vessel directly into a generator, heating the residue in the generator to incandescence by a blast of air, heating the said vessel externally by means of the 115 sensible heat of the blow gases and in addition by burning any producer gas formed, substituting a steam blast for the air blast when the residue is incandescent, passing a portion of the water gas thus produced 120 through the material in the said vessel and burning a portion of the said water gas so as to heat the said vessel externally.

2. A process of gasifying coal and the like, which consists in carbonizing as completely as practicable the material in an externally heated vessel, receiving directly the residue from the said vessel into a generator, heating the residue in the generator to incandescence by a blast of air, burning the 130

producer gas thus formed so as to externally heat the said vessel from above downwards, substituting a steam blast for the air blast when the residue is incandescent, passing a portion of the water gas thus produced through the material in the said vessel, and burning a portion of the said water gas so

as to externally heat the said vessel from above downwards to a sufficient degree to carbonize the material in the said vessel. 10

In testimony whereof I have signed my name to this specification.

ARTHUR McDougall DUCKHAM.
